UNITED STATES PATENT OFFICE.

HENRY J. LAWRENCE, OF LONGBEACH, CALIFORNIA

WAVE OR TIDE MOTOR.

No. 874,687.

Specification of Letters Patent.

Patented Dec. 24, 1907.

Application filed June 18, 1907. Serial No. 379,625.

To all whom it may concern:

Be it known that I, HENRY J. LAWRENCE, citizen of the United States, residing at Longbeach, in the county of Los Angeles and State of California, have invented certain new and useful Improvements in Wave or Tide Motors, of which the following is a specification.

The present invention relates to certain new and useful improvements in the construction of that type of hydraulic motors which are particularly designed for operation by wave power, and aims to provide a motor which will utilize the back flow or current of the under-tow as well as the initial power of the waves.

To this end the invention resides principally in the provision of a motor mechanism comprising a plurality of movable floats or buckets, the said motor mechanism being mounted within a peculiarly constructed casing which causes the initial force of the waves to act upon the floats when moving in one direction and the under-tow to act upon the buckets when moving in the opposite direction.

For a full description of the invention and the merits thereof and also to acquire a knowledge of the details of construction and the means for effecting the result, reference is to be had to the following description and accompanying drawings, in which:

Figure 1 is a longitudinal sectional view through the wave motor. Fig. 2 is a transverse sectional view through the same. Fig. 3 is a horizontal sectional view. Fig. 4 is a detail view of one of the floats and the chain links to which the same is attached.

Corresponding and like parts are referred to in the following description and indicated in all the views of the drawings by the same reference characters.

The motor mechanism proper is mounted within a peculiarly designed casing comprising the spaced sides 1 having their lower portions connected by a pair of transverse walls 2—2, the space between which constitutes a ballast chamber and is adapted to be filled with sand or like material, for the purpose of anchoring the motor in a suitable position upon the bed of the ocean or water-way from which the power is to be derived. A transverse and horizontally disposed partition 3 is supported by the sides 1 toward the upper portions thereof, guide members

4 being located at opposite longitudinal edges of the partition 3. A pair of shafts 5 are journaled between the opposite end portions of the guide members 4, one of the said shafts extending through the casing and having the drive wheel 7 keyed thereon. The corresponding pulleys or sprockets 6 upon the two shafts 5 are connected by belts which are in the nature of the sprocket chains 8. Buckets or floats 9 are carried by these chains 8 at intervals, the said buckets moving forwardly upon one side of the horizontal partition 3 and rearwardly upon the opposite side of the said horizontal partition.

In the specific construction of the floats 9 it will be observed that the same comprise the spaced side pieces 10 having the cross pieces 11 interposed between the extremities thereof. Attention is also directed to the fact that the pivot pins 12 of the chain links 75 to which the floats 9 are attached are extended upon both sides of the chain, one set of extensions entering the ends of the floats while the opposite set are connected by the link members 13 and have the rollers 14 80 journaled thereon. These rollers 14 are designed to engage the upper edge of the guide members 4 and prevent any binding of the floats 9 as the latter are traveling over the upper face of the horizontal partition 3. 85

Ledges 15 are carried by the sides 1 of the casing above the ballast chamber, the said ledges being located below the horizontal partition 3 so as to engage the rollers 14 and prevent sagging or binding of the floats 9 90 when traveling under the partition 3.

One end of the casing is closed by an upwardly inclined wall 16 which extends slightly above the sides 1, the said wall serving to retard the waves and to cause the same to fall upon the floats 9 thereby causing those floats over the horizontal partition 3 to move forwardly. The opposite end of the casing is formed with a mouth 17, the laterally flaring sides of which operate to direct the back flow of the water or the under-tow against those floats 9 under the horizontal partition 3, thereby causing the said floats to travel rearwardly. Suitable outlet ports 18 are formed in the sides 1 of the casing and serve as an exit for the back flow after having acted upon the floats 9. 100 105

Having thus described the invention, what is claimed as new is:

1. In a hydraulic motor, the combination 110

of a casing provided with a ballast receiving chamber, and a motor mechanism mounted upon the casing.

2. In a hydraulic motor, the combination of a casing provided with a ballast receiving chamber, endless belts mounted within the casing, floats carried by the endless belts, and means for directing the water against the floats.

10 3. In a hydraulic motor, the combination of a casing having an upwardly inclined wall at one end thereof and a mouth at the opposite end, endless belts mounted within the casing, and floats carried by the endless

15 belts, the said inclined wall directing the water against the floats when moving in one direction while the water entering through the before mentioned mouth acts upon the floats when moving in an opposite direction.

20 4. In a hydraulic motor, the combination of a casing comprising sides connected by a transverse partition, endless belts mounted within the casing, floats carried by the endless belts and moving in opposite directions

25 upon opposite sides of the transverse partition, and means for directing the water against the oppositely moving floats.

5. In a hydraulic motor, the combination of a casing comprising sides connected by a 30 transverse partition, the said casing having an upwardly inclined wall at one end thereof and a mouth at the opposite end, endless belts mounted within the casing, floats carried by the endless belts and moving in opposite directions upon opposite sides of the transverse partition, the before mentioned inclined walls serving to direct the water against the floats upon one side of the partition while the water entering through the 40 before mentioned mouth acts upon the floats upon the opposite side of the partition.

6. In a hydraulic motor, the combination of a casing comprising sides connected by a transverse partition, guides mounted at

opposite edges of the transverse partition, 45 shafts journaled between the guides, sprockets fast upon the shafts, endless belts connecting the sprockets, floats carried by the endless belts and moving in opposite directions upon opposite sides of the transverse 50 partition, rollers carried by the endless belts for engaging the guide members, and means for directing the water against the floats upon opposite sides of the transverse partition.

7. In a hydraulic motor, the combination 55 of a casing, a transverse partition supported by the casing, a guide member at each side of the partition, a ledge supported by each side of the casing, shafts mounted within the casing, pulleys upon the shafts, bands connecting the pulleys, buckets carried by the bands, and rollers also carried by the bands, the said rollers engaging the guide members when traveling upon one side of the transverse partition and the before mentioned 65 ledges when traveling upon the opposite side of the transverse partition.

8. In a hydraulic motor, the combination of a casing having a mouth at one end thereof and an inclined wall at the opposite end, a 70 transverse partition supported within the casing, and a motor mechanism mounted within the casing and comprising floats moving in one direction upon one side of the transverse partition and in the opposite 75 direction upon the opposite side of the transverse partition, the inclined end of the casing directing the initial force of the waves against the floats moving in one direction while the mouth directs the back flow 80 against the floats moving in the opposite direction.

In testimony whereof I affix my signature in presence of two witnesses.
